STUART PARMELEE MILLER, OF ENGLEWOOD, NEW JERSEY, ASSIGNOR TO THE BARRETT COMPANY, OF NEW YORK, N. Y., A CORPORATION OF NEW JERSEY

DISTILLATION OF TAR

Application filed January 26, 1929. Serial No. 335,207.

This invention relates to improvements in the distillation of tar and the production of distillate oils and pitches therefrom and it includes improvements in both process and apparatus. More particularly, the invention comprises improvements in the distillation of tar at coal carbonization or distillation or gasification and tar production plants.

According to the present invention, the tar to be distilled is heated in an externally heated still or by indirect contact with heating gases, to a temperature above the boiling point of part of the oils contained in the tar, and the resulting preheated tar is discharged into a vapor box where vapors of the lower boiling constituents of the tar are volatilized and from which the vapors are conducted to suitable condensing means. The unvolatilized residue of the tar is then brought in a preheated state into direct and intimate contact with hot fuel gases such as coal distillation or carbonization gases or coal gasification gases to effect further distillation of the tar.

More particularly, the present invention comprises an improved process in which the tar is heated continuously in a pipe coil under pressure to a temperature above the boiling point of part of the constituents. The tar thus heated is fed to a vapor box in which the volatilized constituents separate from the unvolatilized residue, and this unvolatilized residue is then discharged in a preheated state into the still where the residue is brought into direct contact with hot coal carbonization or gasification gases to effect further distillation.

Pipe coil stills have been employed for the distillation of tar by heating the tar continuously in a pipe coil and discharging it into a vapor chamber from which the vapors are drawn off to a condenser and the pitch produced separately drawn off. Such stills are effective for the distillation of part of the oil contained in the tar but if the tar is heated to a sufficient temperature to produce a high melting point pitch and a high oil yield, the temperature is such that considerable decomposition of the oil constituents of the tar

takes place with decrease in oil distilled and increase in carbon and pitch produced.

The present invention includes improvements in the operation of such pipe coil stills in connection with stills in which the gases are brought into direct contact with hot fuel gases and in which the tar is heated in the pipe coil to a temperature sufficient to distill part of the tar constituents but to a temperature insufficient to bring about any objectionable decomposition of the tar. The tar can be readily heated to a high temperature and in a continuous manner in the pipe coil and a considerable distillation accomplished without objectionable decomposition, and after separation of the vapors produced by such heating of the tar, further distillation can be readily accomplished by subsequent distillation of the residue to produce an increased distillation of oil and the production of a higher melting point pitch for further distillation with the hot fuel gases, while nevertheless avoiding any objectionable or considerable decomposition of heavy oil constituents during such further distillation.

When coal tar is introduced into hot coke oven or other coal carbonization or gasification gases, a considerable proportion of the heat contained in the hot fuel gases is consumed in heating the tar to the distillation temperature and in dehydrating it. While there is a large amount of heat available in hot coke oven gases or other coal carbonization or gasification gases for the distillation of tar, yet the B. t. u. content of the gas per unit volume is relatively low and the distillation which can be accomplished per unit volume of gas employed is low. When the hot fuel gases are required to heat the tar and dehydrate it in addition to distilling it, a disproportionately large volume of gases is required and the degree of enrichment of the gases is correspondingly limited so that it is necessary to employ a relatively large volume of gases and to recover the distillate from admixture with such gases.

The present invention enables the distillation of tar by such hot fuel gases to be very greatly promoted and in particular enables a greatly reduced volume of such gases to be

employed to accomplish the desired distillation, and by removal of low boiling constituents from the tar before bringing the tar into direct contact with the hot gases, the difficulties arising from an attempt to completely recover such low boiling oils from the gases are largely avoided.

When tar is distilled by direct contact with highly heated gases such as coke oven gases, the distillates are carried as vapors admixed with the gases leaving the still and these oils are recovered by subsequent cooling of the admixed gases and vapors to effect condensation of the vapors. In order to accomplish such condensation, it is necessary to cool the gases to their dew point for the desired oil constituent which is far below their normal condensation temperatures when free from admixed gases. The complete condensation of lower boiling point oils from admixed gases is difficult and appreciable loss of such light oils may take place unless the gases are subsequently scrubbed to recover them.

The present invention provides an improved process and apparatus in which the light oils are for the most part or completely removed from the tar before it is subjected to distillation by direct contact with the highly heated gases, and in which tar is preheated by indirect contact with hot gases and thus preheated and partly distilled to remove light oils therefrom, and in which the preheated and partially distilled tar is then supplied to the still. The lighter oils which are removed by the preliminary preheating and partial distillation can be readily condensed because they are free from admixed inert gases. The removal of the light oils from the tar before it enters the still greatly reduces the loss of light oils with the gases and greatly improves the condensing operation for condensing the oils from the inert gases. The condensers operated in connection with the still employing the hot coal carbonization gases may be operated at a higher temperature and the higher boiling point oils can be more readily condensed from the gases. The preheated tar enters the still in a preheated condition where its heat is taken advantage of in increasing the unit distillation capacity of the hot gases in the still.

The partial distillation of the tar in the preheater can be supplemented by applying vacuum to the vapor box connected with the preheater thus giving an increased percentage of oils distilled from the tar and the pitch a somewhat higher melting point. The extent to which the distillation is carried in the pre-heating operation can be regulated to a greater or lesser extent by regulating the temperature and amount of the gases employed in the preheating operation and the rate at which the tar and gases pass through the preheater. Where waste flue gases are employed in the preheater, the amount of the

gases passing through the preheater can be regulated to regulate the temperature to which the tar is preheated. By arranging a generally counter-current flow of the tar and of the hot gases, the tar can be preheated to a temperature somewhat lower than that of the hot waste gases.

The temperature required for distilling tar to produce a given percentage of distillate and a pitch of a given melting point in a pipe coil still, is much greater than that required in a still in which the distillation is accomplished by direct contact with hot coal carbonization or hot coal distillation or gasification gases. In the pipe coil still, it is necessary to heat the tar to the distillation temperature of the various oils which are distilled, but in the still in which the tar is heated by direct contact with the hot gases, it is only necessary to heat the tar to a temperature somewhat above the dew point of the gases for such oils.

By preheating the tar and "flashing" it in a vapor box as contemplated by this invention and conveying the heated residue from the vapor box to the still in which the tar is brought into direct contact with the hot gases, a much lower temperature is required for distilling the tar than would be required in an externally heated still, and the preheated and partly distilled tar from the vapor box can readily be further heated and distilled and a pitch of high melting point produced together with an increased percentage of distillate oils without heating the pitch to a temperature where any considerable distillation of oil takes place. The present invention accordingly enables tar to be distilled to produce a high percentage of distillate oils and a high melting point pitch. It also enables tar to be rapidly distilled to produce a lower melting point pitch and a lower percentage of distillate with the production of gases enriched in vapors of higher boiling range from which the distillate can be readily condensed.

It will be appreciated that when tar is distilled by direct contact with hot coal carbonization or gasification gases, the distillate must be recovered from the gases by cooling the gases to the dew points of the gases for the various oil constituents. Ordinarily, coke oven gases, for example, contain only around one to three percent of vapors and the dew point of most of the oil constituents contained in the gases is relatively low. However, by preheating the tar according to the present invention, and then flashing it and then further distilling it by bringing the preheated residue into direct contact with hot coal carbonization gases, the gases can be so greatly enriched in oil vapors that condensation can readily be accomplished at higher temperatures and the condensation can moreover be carried much

more nearly to completion due to the initial 5 separate removal of the lower boiling constituents of the tar in the vapor box. Moreover, the condensation can be carried out fractionally so that heavier and lighter oil fractions can be condensed separately.

The tar which is distilled according to the present invention may be coke oven tar, water gas tar, gas retort tar, producer gas tar, etc. and it may be a total composite tar or a heavier or lighter tar, or blended tars from different sources such as blended water gas and coke oven tar or coke oven and retort gas tar, etc. The tar distilled is advantageously that produced at the plant at which the distillation is carried out so that, for example, coal tar produced at a coke oven plant is distilled at the coke oven plant with the use of hot coke oven gases.

20 The preheating of the tar can readily be carried out at many coke oven or other coal carbonization plants with the use of waste heat. For example, at a coke oven plant equipped with a regenerative preheater, 25 gases leaving the heating flues of the coke ovens and passing to the stack have a large volume and a temperature, for example, around 400° C. In coke ovens having recuperative preheaters for the coke ovens, the 30 gases commonly pass to the stack at a much higher temperature. Coke oven plants having dry quenching systems have an abundance of heat available for preheating purposes. Where waste heat gases are not 35 available, the pipe coil can be heated by the combustion of fuel.

While different types of preheaters can be employed, that which is particularly to be recommended is a pipe coil preheater having a large number of pipes connected together to form a single long continuous coil through which the tar is pumped under pressure and in which the tar is gradually heated to the desired temperature. Such a pipe coil 40 can readily be located, for example, in a flue through which the hot waste flue gases pass from the coke oven heating flues to the stack with flue gases available in large quantities at a temperature around 300 to 400° C. and 45 by providing a pipe coil of sufficient length, the tar can be heated to a high temperature approximating that of the waste gases and it can be readily heated to a lower temperature in a shorter pipe coil or at a more rapid rate. 50 The tar can readily be preheated in such a still to a temperature around 200° C. or even to 300° C. or higher.

The gases employed for the further distillation of the preheated tar after separating 55 the vapors resulting from the preheating operation, may be hot coke oven gases or hot gases from a retort gas plant or other hot coal carbonization or distillation or gasification gases such as producer gas, water gas, etc. Such gases are advantageously em-

ployed at a high temperature approximating that at which they are produced, since with high temperature gases increased distillation can be accomplished and an increased enrichment of the gases in oil vapors attained 70 as compared with lower temperature gases. In the case of coke oven gases, for example, the gases can be withdrawn, e. g. from the individual coke ovens directly into a still which they enter without material reduction in temperature, for example, at a temperature around 500-850° C. or higher, depending upon the type of coke oven, the coking period employed, etc. Even where the gases are partly cooled before being employed for distillation, there will be a greatly increased 75 enrichment of the gases in oil vapors. Where the tar is preheated and then flashed in the manner above described before it is brought into direct contact with the gases for further distillation, the enrichment will be in vapors of higher boiling constituents and there will be comparatively few vapors of lower boiling constituents.

The further distillation of the preheated tar is accomplished by bringing the partially distilled tar into direct and intimate contact with the hot gases, for example, by spraying or atomizing the tar or pitch into the gases. While spray nozzles can be employed for introducing preheated tar into the gases particularly where lower melting point pitches are to be produced, it is more advantageous to employ mechanical spray devices for rapidly spraying the tar and pitch 95 into the gases in a thorough-going manner.

The type of still employed for distilling the pre-heated tar by direct contact with the hot gases can be varied depending upon the amount of tar to be distilled, the temperature 100 of the gases available for distillation, etc. A still having a suitable mechanical spray device such as rapidly rotating rolls or discs dipping into a body of tar or pitch in the bottom of the still, is an advantageous type 105 of still to employ since by sufficiently thorough and intensive spraying of the tar and pitch into the gases, the gases can be rapidly cooled to a temperature approximating that to which the pitch is heated and the pre-heated tar can be rapidly distilled. The partly distilled tar from the vapor box can be discharged directly into the still but it can also and with added advantage in some cases, be discharged into a tower through 110 which the gases and vapors leave the still so that the residue from the vapor box will be still further distilled by direct contact with the hot gases and vapors leaving the still before this partly distilled tar enters the still. 115

The distillate produced by the present process where the hot gases employed are tar laden gases, may contain some heavy tar or pitch constituents where the gases are not thoroughly scrubbed and cleaned before con- 120 125

densation but the percentage of such heavy tar and pitch constituents will be small because of the high enrichment of the gases in oil vapors resulting from the distillation of the tar. Where the gases employed are thoroughly scrubbed and cleaned by the use of an intense and thorough spray of the tar and pitch into the gases, the oil subsequently condensed will be clean oil, that is, free or substantially so from heavy tar and constituents initially entrained in the hot gases.

The extent to which the tar is preheated before being flashed, can be varied. With waste heat preheaters, the preheating may be only to temperatures around 150 or 200° C. or it may be up to 300 or 350° C. but in general it should be below the temperature at which any considerable decomposition of the oil takes place in the externally heated preheater. When tar preheated to such high temperatures is flashed and the residue brought into direct contact with hot gases such as hot coke oven gases, for example, at a temperature of 650 to 850° C. the heat of the hot gases will be employed for distilling the higher boiling oils from the tar, since the preheating will have resulted in the distillation and removal of the lower boiling oils. This further distillation by the hot gases can accordingly be carried out so as to produce a high melting point pitch at a sufficiently low temperature to avoid any considerable decomposition during the distillation, thus giving an unusually high oil yield and pitch of high melting point representing a relatively small percentage of the tar distilled.

The invention will be further described in connection with the accompanying drawings which are of a more or less conventional and diagrammatic character, and which illustrate apparatus embodying the invention and adapted for the practice of the process of the invention at a coke oven plant, but it will be understood that the invention is not limited thereto.

Fig. 1 is a plan view of a coke oven plant equipped for carrying out the invention, and

Fig. 2 is an elevation of the apparatus of Fig. 1, partly in section.

In the drawings, the coke ovens 5 are connected through uptakes 6 with the collector main 7. The gases from the ovens pass through the center box 8 of the collector main into the cross-over main 9 and thence to the condensers 10. This showing of the apparatus is diagrammatic since apparatus of the usual type may be employed.

The gases employed for heating the ovens pass through the flue 13 to the stack 14. By proper manipulation of the valves 15 and 16, a portion of these waste hot gases are bypassed and employed for preheating tar in the preheater 17. The gases then pass to the stack 14 and a blower 19 may be employed

where it is necessary to force the gases through the by-pass.

The tar enters the preheater through the pipe 20 and passes through the preheater where it is preheated above the boiling point for the lowest boiling constituents and is then passed through the line 21 into the vapor box 22 where vapors of the lower boiling constituents separate from undistilled residue. These vapors pass through the main 23 into the condenser 24 where they are condensed and the light oil thus produced is collected in the receiver 25. A portion of the residue from the vapor box may be withdrawn, as a low melting point pitch in the receiver 26. The balance of the residue will be conducted to the still 27.

This residue may be conducted directly to the still or may be added through the spray means 28 located in the tower 29. If the residue from the vapor box is sprayed into the hot gases and vapors leaving the still as shown in the accompanying drawings, the hot gases will further distill the tar before it enters the still. The residue of undistilled tar will collect in the bottom of the tower 29 and will drain through the pipe 30 into the still 27.

The hot gases entering the still are brought from the ovens to the still by means of uptake pipes 31 and the hot gas header 32. By proper manipulation of valves in the uptake pipes 31 and the uptake pipe 6 the hot gases from the ovens connected with uptake pipes 31 may be directed either to the usual collector main 7 or to the hot gas header 32. The hot gases pass from the ovens 5 through the uptake pipes 31 into the hot gas header 32 and thence to the still where they are brought into intimate contact with the tar. This intimate contact is produced by the spray thrown from the roll 33. This roll 33 is so situated within the still that it dips to but a slight extent into the partially distilled tar or pitch in the bottom of the still. The roll is rapidly rotated by means of the motor 34 so that the tar or pitch from the bottom of the still is thrown into the hot gases and forms an intense spray of the tar in the gases. This results in distillation of the tar with minimum decomposition of the tar and also results in thorough scrubbing of the hot gases by the tar. The gases leaving the still through the connecting main 35 into the tower 29 are substantially free from entrained particles. Any entrained spray carried by the gases may settle from the gases in the tower 29 or may be removed by the baffling means 36.

The vapors produced by the distillation of the tar within the still are substantially free from low boiling constituents and may readily be removed from the inert gases in suitable cooling means. The lower boiling constituents have previously been removed

from the tar in the vapor box 22 and have been collected in the storage tank 25. By passing the hot clean enriched gases through the main 37 to the condensers 38 and cooling the gases in the condensers, which cooling need not be to the low temperature ordinarily necessary, a high yield of relatively high boiling oils will be obtained. If direct condensers are employed as shown, the residue from the condensers passes first to a decanter 39 from which the ammonia liquor is drawn off through 40 and the oil which is essentially the higher boiling oils distilled from the tar is collected in 41. An exhauster 42 which may be the same exhauster as that employed for drawing the gases through the ordinary collector main, is employed for drawing the gases through the still and condenser 38. It is to be understood that the apparatus and process of this invention are not to be considered as limited to the specific disclosure described in connection with the drawings. The invention relates to preheating tar, removing vapors from the preheated tar and distilling the residue by direct contact with hot coal carbonization or distillation or gasification gases as claimed below.

I claim:

1. The method of distilling tar which comprises heating the tar in an externally heated still to a temperature sufficient at atmospheric pressure to distill part of the oil from the tar, separating vapors of lower boiling constituents from the preheated tar, separately condensing said lower boiling constituents, and then further distilling the residue from this distillation by direct contact with hot fuel gases while at a high temperature after their production from coal distillation or 40 gasification.

2. The method of distilling tar which comprises preheating tar under pressure to a temperature above the boiling point of part of the oil constituents of the tar, separating vapors of lower boiling constituents from the preheated tar, separately condensing said vapors, and bringing the residue into direct contact with hot coal carbonization or gasification gases and effecting further distillation 50 of the tar by direct contact with such gases.

3. The method of distilling tar which comprises heating the tar continuously in a pipe coil to a high temperature and discharging the resulting tar into a vapor box said temperature being sufficient to distill part of the oil from the tar at the pressure of the vapor box, separating the vapors of the lower boiling constituents from undistilled tar therein, separately collecting and condensing said lower boiling constituents and bringing the partly distilled tar into direct contact with hot coal carbonization or gasification gases to effect further distillation thereof.

4. The improvement in the distillation of tar by direct contact with hot coal carboniza-

tion or gasification gases which comprises preheating the tar to a high temperature under pressure and discharging the thus preheated tar into a vapor box said temperature being sufficient to distill part of the oil from the tar at the pressure of the vapor box, separating the vapors of lower boiling constituents from undistilled residue therein and separately condensing them, and discharging the undistilled residue in a preheated state 70 into direct contact with the hot coal carbonization or gasification gases to effect further distillation at substantially atmospheric pressure.

5. The improvement in the distillation of tar in pipe coil stills which comprises heating the tar continuously in a pipe coil, discharging the tar therefrom into a vapor separating chamber the heating of the tar being regulated so as to heat the tar to a temperature 80 sufficient to distill part of the oil therefrom at the pressure of the separating chamber, separately collecting and condensing the vapors from the vapor separating chamber, withdrawing undistilled residue from the 85 vapor separating chamber, passing the preheated residue into a still and subjecting it to intimate and thorough contact in the form of a spray with a current of hot coal carbonization or gasification gases to effect further distillation, and passing the resulting gases and 90 vapors in direct contact with the preheated tar residue before the residue enters the still.

6. The method of distilling tar which comprises preheating the tar continuously in a pipe coil to a temperature above the boiling point of part of the tar constituents, discharging the preheated tar into a vapor box, separating the vapors from undistilled residue therein and separately cooling said vapors to recover oils therefrom, bringing the undistilled residue into direct contact with hot coal carbonization or gasification gases to effect further distillation of the same, such further distillation being effected by a repeated and intense spraying of the partly distilled tar into a current of the hot gases, and drawing off gases and vapors resulting from such distillation and cooling the same to condense oils therefrom.

7. The method of distilling tar at a coke oven plant which comprises preheating the tar continuously in a pipe coil still by waste heat gases, discharging the preheated tar into a vapor box the preheating of the tar being regulated so as to heat the tar to a temperature sufficient to distill part of the oil therefrom at the pressure of the vapor box, separating the tar from the vapors therein whereby vapors of lower boiling constituents are separately collected and condensing said vapors, introducing the preheated residue from the vapor box into direct contact with a current of hot coke oven gases, thoroughly spraying the tar or pitch into the

- gases thereby scrubbing the gases and further distilling the preheated tar, and drawing off the resulting gases and vapors, and cooling the same to condense oils therefrom.
- 5 8. The method of distilling tar at a coke oven plant which comprises preheating the tar continuously in a pipe coil still by waste heat gases, discharging the preheated tar into a vapor box the preheating of the tar being 70
 10 regulated so as to heat the tar to a temperature sufficient to distill part of the oil therefrom at the pressure of the vapor box, maintaining reduced pressure on the vapor box, separating the vapors from undistilled residue 75
 15 due within the vapor box and separately collecting such vapors and cooling them to recover low boiling constituents therefrom, and introducing the residue from the vapor box into direct contact with hot coal carbonization 80
 20 gases to effect distillation thereof.
9. An apparatus for distilling tar comprising in combination with coal carbonization or gasification apparatus, a still, means for passing coal carbonization or gasification 85
 25 gases from said apparatus into the still a preheater for preheating the tar, a vapor box for separating vapors from undistilled residue of the preheated tar, means for separately condensing said vapors, and means for mingling the preheated residue from the vapor box with hot coal carbonization or gasification 90
 30 gases in the still.
10. An apparatus for distilling tar comprising in combination with coal carbonization or gasification apparatus, a still, means for passing coal carbonization or gasification 95
 35 gases from said apparatus into the still, means for withdrawing from the still the gases and vapors resulting from the distillation, means for cooling them to condense oil 100
 40 therefrom, means for preheating the tar under pressure, a vapor box for separating vapors thus produced from undistilled residue of the preheated tar, separate condensing means for said vapors, means for discharging the residue from the vapor box into the hot gases and vapors leaving the still, means for then bringing the partially distilled tar into the body of the still, and means for 105
 45 bringing about intimate contact of the tar or pitch in the still with the gases, and means for withdrawing the resulting pitch from the still.
11. An apparatus for distilling tar comprising in combination with coal carbonization or gasification apparatus, a still, means for passing coal carbonization or gasification 110
 55 gases from said apparatus into the still, means for withdrawing from the still the gases and vapors resulting from the distillation, means for cooling them to condense oil 115
 60 therefrom, a pipe coil preheater for preheating the tar by bringing it into indirect contact with hot flue gases coming from a coal distillation or coal carbonization plant, a vapor box for separating vapors from undistilled residue, separate condensing means for said vapors, and means for conveying the preheated tar to the vapor box, and means for conveying residue from the vapor box to the still.
